[57] CLAIM

The ornamental design for a boat rope controller, substantially as shown and described.

DESCRIPTION

FIG. 1 is a perspective view of a boat rope controller showing my new design;

FIG. 2 is a left side elevational view of the boat rope controller of FIG. 1;

FIG. 3 is a top plan view thereof;

FIG. 4 is a right side elevational view of the boat rope controller of FIG. 1;

FIG. 5 is a back elevational view thereof;

FIG. 6 is a front elevational view thereof; and

FIG. 7 is a bottom elevational view thereof.

A boat rope used for water skiing and other aquatic sports, anchoring and general towing is stored in, dispensed and retrieved by the boat rope controller.

The broken lines in FIG. 1 are for illustrative purposes only.
